J. HOJNOWSKI

SECTIONAL RAILWAY TIE

Filed March 31, 1927

Jakob Hojnowski Inventor

UNITED STATES PATENT OFFICE.

JAKOB HOJNOWSKI, OF NEKOOSA, WISCONSIN.

SECTIONAL RAILWAY TIE.

Application filed March 31, 1927. Serial No. 179,956.

This invention relates to improvements in railroad ties, and it is the principal object of my invention to provide a sectional tie facilitating the handling of the same, and allowing a use of the tie for tracks of different gage.

Another object of my invention is the provision of a railway tie equipped with novel and improved means for uniting the several sections and holding the same together.

A further object of my invention is the provision of a sectional tie of this character allowing the interposition of one or more median sections between the parts of the tie proper whereby longitudinally extending bars are used to which the eye-bolts of the intermediary sections are held to hold all parts in their proper relative position.

These and other objects of my invention will be more fully set forth in the following description and will then be specifically defined in the appended claim.

In the accompanying drawing, forming a material part of this disclosure:

Fig. 1 is a side elevation of a sectional railroad tie constructed according to my invention.

Fig. 2 is a top plan view of the tie made in two sections illustrating the means for combining the same.

Fig. 3 is a top plan view of the tie with the central sections removed.

Fig. 4 is a sectional end view on line 4—4 of Figure 3.

The tie, preferably of reinforced concrete or any other suitable material, is composed of two main parts or sections 10 and 11 adapted to support the rails 12 and 13 respectively of a track, the foot flanges of which are held in place on the tie by means of the rail foot engaging clamps or plates 14, each having a central slot 15 allowing the passage and adjustment of fastening bolts 16 carrying at their upper threaded ends the counter nuts 17, 18, and having inner projecting rail foot engaging or gripping plates or flanges 19.

Longitudinally extending bars 20 are

united at the outer ends of the tie parts by means of end plates 21 through which said bars extend with their outer threaded ends which carry nuts 22.

The inner oppositely disposed ends of the tie parts 10 and 11 are suitably recessed, as at 23, and connecting cross-bars or links 24 are passed through these recesses, and carry outer eye-shaped end loops 25 through which the bars 20 pass.

The median intermediate sections 26, 27 of the tie which may be used in any desired number have also recesses 28 formed at their meeting faces for the passage of the bars 24 through the end or terminal loops or eyes of which the bars 20 pass.

The operation of my novel tie and its use will be entirely clear from the above description without further detailed explanation and it is to be understood that such changes as come within the scope of the appended claim may be made in the general arrangement and in the construction of the minor details of my sectional tie without departing from the spirit of my invention.

Having thus described my invention, what I claim as new, and desire to secure by Letters Patent is:

In a sectional, recessed railroad tie, means for securing and holding the sections together, said means comprising cross-bars arranged in recesses at the inner end faces of the tie-sections, eyes formed at the ends of said cross-bars, and longitudinally extending bars passing through said eyes and embedded in recesses formed in the sides of the tie for holding and securing the end sections and a desired number of intermediary sections in their relative positions, and outer end plates on the sections adapted to be engaged by fastening means upon the ends of said longitudinal bars for holding the same in position and for adapting the ties to tracks of desired gage.

Signed at Nekoosa, in the county of Wood and State of Wisconsin.

JAKOB HOJNOWSKI.
